Jacob Kinzer's "Diamond Cutter" Tobacco Knife. - ~~Design~~ =

4036

PATENTED MAY 17 1870

United States Patent Office.

JACOB KINZER, OF PITTSBURG, PENNSYLVANIA.

Design No. 4,036, dated May 17, 1870.

DESIGN FOR A TOBACCO-KNIFE.

The Schedule referred to in these Letters Patent and making part of the same

I, JACOB KINZER, of Pittsburg, in the county of Allegheny and State of Pennsylvania, have invented and produced a new and original Form of Tobacco-Knife or Cutter, the nature of which design is fully represented in the accompanying perspective drawing forming part of this specification.

Claim.
I claim as my invention—
The design for a tobacco-cutter, as shown.
Witnesses: JACOB KINZER.
